UNITED STATES PATENT OFFICE.

FRANK P. TRAINOR, OF UNIONTOWN, PENNSYLVANIA.

DETACHABLE-POINT PICK.

1,111,277.

Specification of Letters Patent. Patented Sept. 22, 1914.

Application filed January 22, 1913. Serial No. 743,446.

To all whom it may concern:

Be it known that I, FRANK P. TRAINOR, citizen of the United States, residing at Uniontown, in the county of Fayette and State of Pennsylvania, have invented certain new and useful Improvements in Detachable-Point Picks, of which the following is a specification.

My invention relates to picks, and particularly to picks provided with detachable points.

The primary object of my invention is the provision of a very simple, readily repaired and readily assembled pick, particularly adapted for miners' use, in which the pick points are detachable from the head of the pick, and in which the handle of the pick is held firmly in engagement with the head of the pick and with the pick points but permitted to be readily removed from the head of the pick when desired.

A further object of the invention is to so connect the pick points to the head of the pick that they will be held firmly in place to withstand the shocks to which the pick points are subjected.

A still further object is to so connect the pick points to the handle and to the head that the handle will not become loose within the head of the pick but will be clamped firmly in engagement therewith at all times.

Other objects will appear in the course of the following description.

For a full understanding of the invention, reference is to be had to the following description and accompanying drawing, in which:—

Figure 1 is a perspective view of a pick constructed in accordance with my invention; Fig. 2 is a longitudinal section of my improved pick head with detachable points; Fig. 3 is an under side plan view of the head, the points being removed; Fig. 4 is a section on the line 4—4 of Fig. 2; Fig. 5 is a perspective detail view of the wrench whereby the collar may be removed; Fig. 6 is a perspective detail view of the liner which is disposed between each tang and the handle.

Corresponding and like parts are referred to in the following description and indicated in all the views of the drawing by the same reference characters.

In the drawings, 2 designates the head of the pick. This head is preferably cast and is provided with the two laterally projecting oppositely disposed portions 3. The

head of the pick is formed with an eye 4, oval in shape, and into which the large end of the handle is received, and is also formed with opposed downwardly extending handle 60 engaging spaced socket members 5. The interior faces of these socket members are slightly concave to engage with the rounded faces of the handle, while the outer faces of these downwardly projecting socket members 65 are screw-threaded, as at 6, to engage with an interiorly screw-threaded clamping collar or nut designated 7.

The under faces of the arms or extensions 3 of the head are longitudinally grooved or cut-away as at 8. The side walls 9 of this groove are under-cut or downwardly and inwardly beveled as at 9^a so that the groove is dovetailed in shape. Projecting from the ends of the arms 3 and formed integral 75 therewith, and therefore integral with the head, are the tenons 10 which are preferably rounded or circular in section, the lower faces of these tenons being co-incident with the inner faces of the recessed portions 8 20 of the head. The head is preferably cut-away at opposite points, as at 11, leaving openings which extend through the walls of the head.

There are two pick points, one for each 85 end of the head, both of these pick points being alike. Each point is tapered from its basal end to its apex, and each point is preferably square in section. The points are designated 12. The base of each point is 90 formed with a mortise 13 to receive the tenon 9, and from the base at the under side thereof projects a tang or extension 14 which has beveled side edges 15 adapted to engage with the beveled side walls 10 of the recess 95 8. The tang is then narrowed and curved downward, as at 16, so as to conform to the curvature of the head of the pick handle, and then extended vertically downward, as at 17, this vertical portion of the tang being 100 laterally curved to conform to the curvature of the handle. The curved portion 16 and the straight portion 17 of the tang 14 are formed with inwardly projecting pointed studs or prongs 18 adapted to engage with the wood of the handle. These studs are preferably screwed into the tang 14, but I do not wish to be limited to this particular manner of mounting the studs upon the tang.

It will be noted that the curved portion 16 and the straight portion 17 of each tang

14 is adapted to fit between the downwardly extending laterally disposed socket members 5 so as to form, when in place, a continuation of the walls of said socket members. The outer face of each tang 16 is exteriorly screw-threaded, as at 19, to correspond with the exteriorly screw-threaded portion 6 of the socket members 5 and to engage with the nut or collar 7.

10 The handle 20 has any ordinary or usual form and is approximately oval in cross section, and at its upper end is formed with an enlarged head 21 which fits within the eye 4. The portions 16 of the tangs 14 of each 15 pick point corresponds in curvature to the curvature of the opposite edges of this head 21, and when the pick points are in place the studs or prongs 18 project into the wood of the handle. Preferably the wood of the 20 handle is bored at proper points to receive these prongs or studs.

It is to be particularly noted that as the collar or nut 7 is screwed home, it will force the curved tangs of the pick points firmly 25 against the curved edges of the head 21 and force the prongs or studs 18 into firm engagement with the wood of the head, and furthermore, that the nut or collar as it is 30 screwed home will cause the portions 16 and 17 of the tang 14 to clamp firmly against the hammer and shank of the handle, so that the handle will be held rigidly in position against any movement, thus preventing any loosening of the head upon the handle. 35 Furthermore, the tightening of the collar or nut 19 upon the head will draw the pick points into snug engagement with the tenons 13 and cause the base of the pick points to abut firmly against the ends of the arms or 40 extensions 3 of the head, so that when the nut 7 is fully tightened up the pick points will be nearly as rigid with the head as if they were cast in one piece therewith.

It is to be further noted that the strain 45 on the pick points incident to use is resisted not only by the tenon 13 fitting into the mortise in the pick points but by the tang 14 which bears against the under face of the head of the pick and that portion of the tang which extends down along the handle 50. And furthermore, this wrenching strain upon the pick point caused by the impact of the point against a solid body is resisted by the co-acting dove-tailed faces of the tang 14 and the side walls 9 of the arms 3. This 55 dove-tailed engagement between the tang 14 and the portions 3 of the head also prevents any downward movement of the pick point relative to the head.

60 For the purpose of assembling and disassembling the pick, I provide an ordinary form of wrench, illustrated in Fig. 5, comprising a shank 22 having a semi-circular curved portion 23 at one end, this curved 65 portion being provided with an inwardly

projecting stud 24 adapted to engage in an opening 25 in the nut or collar. In order to provide an implement which may be used not only for removing and replacing the nut 7, but also for forming recesses in the head 21 of the handle for the reception of the studs 18, I preferably provide the shank 22 with a gimlet end 26.

The operation of my invention will be obvious from what has gone before. In order to disassemble the pick, it is only necessary to remove the nut or collar 7 and withdraw the points from engagement with the handle, after which the handle may be also removed. In assembling the members, the handle is first inserted in the head and the points are then slid into place and the nut 7 is engaged to draw the parts into operative position.

My invention is simple, may be readily manufactured, and is thoroughly effective in actual use. The chief objection to picks heretofore used for the same purpose as mine is designed for has been that the points were too readily disengaged from the head, and that the points shortly become loose so that a full strong stroke could not be struck. This is not the case with my pick. The points are held in solid engagement with the head and cannot become detached while in use. Furthermore, the handle is also held in rigid engagement with the head and the inconvenience incident to a loosened handle is entirely obviated.

In Fig. 6, I have shown a liner designated 27 consisting of a strip of metal curved to conform to the curvature of the side edge of the pick handle and disposed between the end of the tang and the handle. This liner is perforated for the passage of the corresponding stud 18.

Having thus described my invention, what I claim as new and desire to secure by Letters Patent is:—

1. A pick comprising a head having oppositely disposed ears constituting a handle socket and oppositely projecting arms each longitudinally recessed on its under face, pick points abutting against the ends of the arms, the adjacent faces of the points and of the arms having one a tenon and the other a mortise for receiving said tenon and each pick point having a tang or extension engaging in said recess, said tang being downwardly extended, and means engaging the downward extensions of the tangs and said ears.

2. A pick comprising a head having oppositely disposed ears constituting a handle socket, the exterior faces of said ears being screw-threaded, said head having oppositely disposed arms, each longitudinally recessed on its under face, the side walls of each recess being under-cut, and each arm formed with a tenon at its end, pick points abutting

against the ends of said arms, the base of each point being formed with a mortise to receive the corresponding tenon on the end of the corresponding arm, each point having 5 a tang extending from the base thereof and formed with beveled side edges and engageable with the walls of said recess, the extremity of each tang being downwardly turned to fit between the ears of the handle 10 socket, each downwardly turned portion of the tang being exteriorly screw-threaded, and a nut engageable with the screw-threads of the tang and the ears.

3. A pick comprising a head having oppositely projecting arms, pick points abutting against the ends of the arms, the adjacent end faces of each pick point and the corresponding arm being formed one with a tenon and the other with a mortise receiving 15 the tenon and each pick point having an extension or tang provided with a plurality of studs or prongs, a handle with which said studs or prongs engage, and means engaging the tangs of the pick points and holding the tangs in engagement with the handle and pick points abutting against the head.

20 4. A pick comprising a head having oppositely disposed segmental ears surround-

ing an eye and being exteriorly screw-threaded, the ears being spaced from each other, said head being formed with oppositely projecting arms each longitudinally recessed on its under face, the walls of each recess being under-cut, pick points abutting against the ends of said arms, the abutting 25 ends of the arms and points, one having a tenon and the other a mortise to receive the tenon and each pick point having a tang provided for a portion of its length with beveled side edges engaging the under-cut 30 walls of the corresponding recess, the end of the tang being downwardly bent to lie between the said ears and being exteriorly screw-threaded, said end being provided on its inner face with inwardly projecting 35 studs to engage the handle, a handle having its head disposed within the eye of the pick head and embraced by said ears and said tangs, and an interiorly screw-threaded nut 40 engaging the ears of the tangs.

50 In testimony whereof I affix my signature in presence of two witnesses.
